BOTTLE WASHER

John P. McKinley and Wilbert P. Ackland, Buffalo, N. Y.; said Ackland assignor to said McKinley

Application January 27, 1937, Serial No. 122,560

17 Claims. (Cl. 141—7)

This invention relates to bottle washing mechanism of the type in which the bottles are subjected to a series of different cleansing treatments, and where the dirty bottles are introduced at one point, and cleaned and sterilized bottles removed at another point.

An object of this invention is to provide an improved bottle washing mechanism of the type utilizing an endless conveyor with pockets for carrying the bottles while they are subjected to the various cleansing treatments, and which will have improved means for tightening the conveyor when such tightening is necessary due to wear, stretching or other causes.

Another object of the invention is to provide an improved bottle washing mechanism with improved means for screening foreign matter from the washing or rinsing liquid which is being recirculated and discharged against the bottles for cleansing or rinsing the same, with which the screen may be easily inspected and removed for cleaning from a position at the side of the machine in a simple and easy manner, and which will be relatively simple and inexpensive.

Another object of the invention is to provide an improved means for delivering the dirty bottles to the endless conveyor which carries the bottles through the various cleansing stations.

Another object of the invention is to provide an improved, automatic pre-rinsing device for said bottles and which may form an attachment for existing types of bottle washing machines, or which may be constructed as a physical part of the bottle washing machines.

Another object of the invention is to provide improved pre-rinsing mechanism for bottle washing machines, with which the bottles may be subjected to a pre-rinse of relatively long duration before being passed through the soaking tank, with which the pre-rinse liquid will be discharged only while the bottle holders are in selected positions, and which will be convenient, compact, efficient and inexpensive.

Another object of the invention is to provide improved means for loading bottles in groups into an endless bottle conveyor, and which will be particularly simple, effective, convenient and inexpensive.

Another object of the invention is to provide an improved and simplified mechanism for loading bottles to be cleaned into a bottle washing machine.

Various other objects and advantages will appear from the following description of an embodiment of the invention, and the novel fea-

tures will be particularly pointed out hereinafter in connection with the appended claims.

In the accompanying drawings:

Fig. 1 is a side elevation of a bottle washer constructed in accordance with this invention and having attached thereto a bottle pre-rinse and automatic loading mechanism constructed in accordance with this invention;

Fig. 2 is a transverse sectional elevation through a portion of the same, the section being taken approximately along the line 2—2 of Fig. 1;

Fig. 3 is a longitudinal sectional elevation of the same;

Fig. 4 is a longitudinal sectional elevation through a portion thereof in a different longitudinal plane than that shown in Fig. 3, and illustrating the improved means for tightening the conveyor chain;

Fig. 5 is a side elevation of the loading end of the machine, the elevation being at the opposite side from that shown in Fig. 1;

Fig. 6 is a sectional plan through a portion of the same at the pre-rinse mechanism, the section being taken approximately along the line 6—6 of Fig. 5;

Fig. 7 is a sectional elevation through a portion of the same, the section being taken approximately along the line 7—7 of Fig. 6; and

Fig. 8 is a transverse sectional elevation through a portion of the same, the section being taken approximately along the line 8—8 of Fig. 7.

In the illustrated embodiment of the invention, the improved bottle washing mechanism is largely housed in a casing or housing 10 of any suitable shape and construction, and within this housing and extending from end to end thereof is an endless conveyor 11 provided with a series of pockets 12, Fig. 3, arranged in succession lengthwise of the chain. The pockets are supported in rows, Fig. 6, which extend crosswise of the conveyor, the pockets of the different rows being supported by transverse frame members 13, Fig. 6, which extend between and are secured to links 14 forming endless chains extending along each side wall of the housing. The frame members 13 are secured to the links 14, Fig. 4, in any suitable manner such as by bolts 15.

The links 14 at each side of the housing are disposed approximately end to end but in slightly overlapping relation, and are connected by pivot pins 16 which laterally from the connected links and carry rollers 17. The two endless chains formed of the links 14 at each side of the housing are identical with one another and are con-

nected by the frame members 13, Fig. 6, so that the two chains will move in unison with one another and carry the rows of pockets successively from end to end of the housing. The rollers 17 are on the outside of the conveyor, in close proximity to the inner faces of the vertical side walls of the housing 10, and run on trackways 18 provided on the inner faces of the vertical side walls of the housing.

Each trackway may be conveniently formed by attaching angle bars or angle strips to the side wall of the housing, and approximately end to end with one another, so as to provide flanges extending into the housing from each side thereof upon which flanges the rollers 17 ride. The trackways 18 are arranged in an approximately endless loop to provide an upper stretch which is slowly rising towards the loading end, a downwardly and forwardly inclined end stretch at the loading end of the machine leading from the upper stretch, a horizontal, lower stretch running closely along the bottom wall of the housing and leading from the end stretch, and a rising section at the rear end of the machine connecting the upper and lower stretches.

The bottom portion of the housing is made water tight and functions as a soaking tank into which the endless conveyor moves at the loading end and from which it emerges at the opposite or rear end. The trackway for guiding this lower stretch of the conveyor in the soaker tank may, if desired, be formed at each side of the housing of two angular strips with the projecting flanges slightly spaced apart, or a channel strip in which the rollers 17 run may be used, so as to prevent the conveyor from dragging on the bottom of the soaker tank or housing. It is undesirable to provide sharp bends where the upper, lower and end sections of the conveyor join one another, and for that reason the trackway is curved through arcs of substantial radius where the upper and lower stretches join the end sections.

The bottom wall of the housing at the forward or loading end of the machine is curved upwardly as at 19, so as to extend parallel to the curved trackway for the purpose of acting as a guard to prevent the bottles from dropping out of the pockets as the pockets descend into the soaker tank. An arcuate guard plate 20 is disposed at the opposite or rear end of the housing and extends upwardly along but spaced from the arcuate trackway at the rear end of the housing, so as to keep the bottles confined in the pockets leaving the soaker tank until the pockets reach a position in which the bottles will be retained therein by gravity.

The pockets have their ends facing the interior of the closed loop of the conveyor about which they move, small enough so that the bottles cannot pass therethrough, but the outer ends of the pockets are open. As the pockets move along the lower stretch with the conveyor, the bottles will tend to fall out by gravity, but are confined within the pockets by the arcuate end walls 19 and 20 and the bottom wall of the housing. The bottles are kept in the other stretches of the conveyor by gravity as will be observed from Fig. 3. This type of conveyor is well known in the art, and per se forms no part of this invention.

An endless conveyor of this type has a tendency to stretch slightly in use, and to lengthen slightly through wear, and therefore a limited adjustment for tightening the chain is desirable.

An improved and simple manner of tightening the chain is illustrated particularly in Figs. 3 and 4, where the arcuate section 21 of the trackway 18 which joins the rising end stretch at the rear end of the machine to the rear end of the upper stretch of the trackway 18 is made separate and adjustable. Each arcuate section 21 of the trackway has its ends 22 flared toward the center of the loop slightly so as to guide the rollers 17 smoothly from one stretch or section to another, and is mounted on a plate 23 disposed along the adjacent side of the housing. Each plate 23 is provided with a plurality of slots 24 which extend generally parallel to one another and to the bisector of the angle between the rising rear end section of the conveyor and the upper stretch of the conveyor. Bolts 25 pass through these slots and through the side walls of the housing where they carry nuts 26, Fig. 1.

A link 27, Fig. 4, is disposed at each side of the housing, and each is connected at one end by a pin 28 to the adjacent plate 23 and at its other end it extends through the housing at the rear upper corner thereof, where it carries a washer 29 and a nut 30. Thus by tightening the nut 30 at each side of the housing the links 27 may be drawn outwardly so as to slide the plates 23 outwardly, and thus force the arcuate trackway sections 21 outwardly and tighten the chain or conveyor, as shown clearly in Fig. 4. After the desired tightening movement, the nuts 26 are tightened, which effectively locks or clamps the plate 23 in adjusted positions. The tightening is accomplished by the adjustable section at the upper part of the housing where there is no danger of leakage of the washing liquids, and where a very slight movement of the plates 23 will produce a very effective tightening of the conveyor.

A wall 31, Fig. 3, is provided just above the pockets in the lower stretch of the conveyor, and the ends of this wall extend upwardly at 32 and 33. The wall 31 extends between and connects the side walls of the housing so as to provide a water tight compartment above the soaker tank section 34 provided between the wall 31 and the bottom of the housing. Transverse walls 35 and 36 project upwardly from the wall 31 intermediate of its ends and also extend between and connect the side walls of the housing so as to form upwardly opening tanks 37 and 38 which lie immediately below the upper stretch of the conveyor and above the soaker tank. A washing liquid is contained in the tank 37 and rinsing water is contained in the tank 38.

One side wall of the housing which forms a side wall of each of the tanks 37 and 38 is provided with outwardly extending, projecting chambers 39 and 40, Figs. 1 and 2. These projecting chambers are somewhat triangular in shape in transverse cross section, as shown clearly in Figs. 1 and 2, and the top wall 41 of each is removable and provided with a handle 42, to enable access to be had to the interior of the housing and projecting chamber from the exterior of the housing. These projecting chambers 39 are provided, adjacent or adjoining one of the end walls of the tanks 37 and 38, such as adjoining the walls 33 and 36, with intermediate, triangular shaped walls 43 and 44, Fig. 3, which are disposed parallel to the walls 33 and 36 and extend from the projecting chambers 39 partly across the tanks 37 and 38.

The surfaces of the walls 33 and 43, Fig. 3, which face one another are provided with guides

45 and 46, Fig. 2, which form between them an inclined guideway or groove in which an inclined screen 47 is secured by sliding it downwardly through the upper end of the projecting chamber 39. By removing the cover 41, one may inspect the upper inclined surface of the screen 47, and also remove the screen by pulling it upwardly along the guideways or grooves formed by the guides 45 and 46. Thus the screen may be removed for cleaning, repairs or replacement, and be reinserted into the tank merely by sliding it downwardly into position through the projecting chamber 39. The walls 33 and 43 and the screen form a triangular chamber 48 adjacent the side of the housing which communicates with the main body of the tank 31 solely through the surface of the screen.

An outlet pipe 49 opens through the side wall of the housing 10 into the compartment 48, for conducting the washing solution to a pump 50, from which the washing fluid is delivered, by a pipe 51 having suitable branches, to spray devices which direct it against the bottles in the portion of the upper stretch of the conveyor which is immediately above the tank 31. Any solid matter washed from the bottles in this manner will drop downwardly into the tank 31, and it will be held back by the screen 47 from entering the pipe 49 where it might clog the pump or the spray devices supplied by the pipe 51.

The walls 44 and 36 also have between them guideways similar to those shown in Fig. 2 for the tank 37, and mount, in the same manner, a screen 52 which is insertable and removable through the projecting chamber 40 in the manner explained in connection with the screen 47 and chamber 39. Thus, any foreign matter in the tank 38 will be screened out. A pipe 53 opens into the tank 38 beneath the screen 52, and thus the entry of foreign matter into the pipe 53 will be prevented. The pipe 53 connects with the pump 54 which delivers the rinse water under pressure through the pipe 55 to suitable spray devices 56 arranged above the tank 38.

The upper end of the wall 36 is bent horizontally and toward the loading end of the machine, and provided with upstanding flanges to form a pan 57 also disposed beneath the upper stretch of the conveyor. Spray devices 58 are arranged above the pan 57 for spraying fresh rinsing water into and upon the bottles in the pockets over the pan 57, and the water therefrom drains into the pan 57. The drain pipe 59 connects the pan 57 to an overflow pipe 60 and to the tank 38.

A valve 61 in the pipe 60, and a valve 62 in the connection from the pipe 59 to the tank 38, makes it possible to divert any desired portion of the rinse water from the pan 57 into the tank 38, and the remainder is delivered through the pipe 60 to a suitable drain. Another pan 63 is disposed adjacent the pan 57, but further forwardly, and contains a chlorine solution for sterilizing the bottles. A pipe 64, Fig. 3, connects the chlorine tank to a pump, not shown, from which the chlorine water is delivered by a pipe 65, Fig. 1, to a chlorine water spray device 66, Fig. 3, where the chlorine water is sprayed into the rinsed bottles.

On the outside of the housing a pair of valves 67, Fig. 1, are arranged one in front of the other for operation by levers 68 and 69. The valve 67 nearest the housing is included in the pipe 65 so as to control the chlorine water supplied to the

spray devices 66. The valve arm 68 is operated at intervals by a cam 70 mounted on a shaft 71, Figs. 1 and 3, which is driven through suitable speed reduction mechanism 72 from a motor 73, Fig. 3. The speed reduction mechanism and motor are conveniently disposed within the housing above the wall 31 and beneath the pans 57 and 63.

A crank arm 74, Fig. 1, is also mounted on the shaft 71 and connected through a link or connecting rod 75 to an arm 76 mounted on a shaft 77 at the top of the housing. This shaft extends across the top of the housing and carries a pair of arms 78, Fig. 3, at each side of the housing which depend into the housing and are pivotally connected by pins 79 to feeding dogs 80 which operate on the rollers 17 of the conveyor to feed the same forwardly along the upper stretch of the trackway. Thus as the motor 73 operates, the dogs 80 will be retracted and then pushed forwardly so as to impart intermittent increments of movement to the conveyor in a direction to move the upper stretch of the conveyor to the loading end of the machine, and downwardly into the front end of the soaker tank.

The shaft 71 extends entirely across the interior of the housing, and upon the outside of the housing at the side opposite the crank arm 74, the shaft 71 is provided with a pair of cams 81 and 82, Fig. 5. The cam 82 has a cam groove 83 opening outwardly away from the housing, and a roller or cam follower 84, provided on an arm 85 runs in the groove 83. The arm 85 is pivoted at 86, and at its free end it is pivoted at 87 to one end of a link 88, the other end of the link being pivoted by a pin 89 to an arm 90 fixed on a shaft 91. The shaft 91 extends across the interior of the housing, Figs. 3 and 6, and near each side of the housing, but within it, a pair of arms 92, Figs. 3 and 6, are fixed on shaft 91 and extend upwardly and rearwardly therefrom.

The arms 92 at their upper ends have slots 92a which receive a cross member 93 that at its ends carries rollers 93a. These rollers run in parallel slots 93b in the housing, and a plurality of bottle ejectors 94 are pivoted on the member 93. These ejectors 94 at their free ends extend through slots or guides in a plate 95 which is slidably mounted on a support or cross bar 96, and shifted vertically by a screw 97, so as to align the free ends of the ejectors 94 with the inner ends of the pockets when the pockets are stationary between increments of movement of the conveyor. Thus as the cam 82 rotates, the arm 85 will be oscillated and through the link 88 will oscillate arm 90 and shaft 91.

This oscillation is so timed by the character of the cam groove 83 that the ejectors 94 are forced into the pockets aligned therewith during the interval while the conveyor is stationary, that is, while the feed dogs are moving to a new feeding position, and the ejectors 94 upon entering the bottle pockets forcibly eject the bottles therefrom. The ejected bottles are received upon a pivoted support 98, which at the proper time is rocked upwardly to deposit the bottles resting thereon upon a conveyor device 99 as usual in this type of washer. Continued movement of the cam 82 rocks the shaft 91 and the arms 92 to retract the ejectors 94 before the next forward movement of the feeding dogs 80.

At one side of the housing, the shaft 91 has fixed thereon an arm 100, Figs. 1 and 6, and the upper end of this arm is connected by a link 101

to a crank arm 102 loose on a stub shaft 103 of a pre-rinse and loading mechanism which will now be described. A loading element 104 has the stub shaft 103 at one end thereof and a corresponding and aligned stub shaft 105 at the other end thereof, by which the element 104 may be suitably mounted for rotation about an approximately horizontal axis. The stub shafts 103 and 105 are rotatably mounted in bearings provided in the end walls of an auxiliary housing 106 which fits against the front end of the housing 10. The stub shaft 103, after passing through the end wall of the housing 106 carries a ratchet wheel 107 fixed thereon, this wheel having ratchet teeth upon its periphery.

A ratchet pawl 108 is pivoted on the pin which connects the link 101 to the crank arm 102, and at its free end it rides upon the periphery of ratchet wheel 107 so as to engage with the ratchet teeth thereof. The crank arm 102 extends upwardly from the shaft 103 and the pawl 108 is urged downwardly by gravity into engagement with the ratchet teeth of the ratchet wheel 107. Thus as the shaft 91 oscillates, the arm 100 will also oscillate and through the link 101 it will rock the loose crank arm 102 about the shaft 103. During the oscillation of the arm 102 in one direction, the pawl 108 will engage with the teeth of the ratchet wheel and turn it through a fraction of a rotation, and then when the arm 102 oscillates in the other direction, the pawl 108 will be retracted to a position in the rear of another ratchet wheel tooth.

In the particular illustrated embodiment, there are four ratchet teeth provided in the periphery of the ratchet wheel 107, and those teeth are evenly spaced around the periphery of the ratchet wheel, so that each time that the arm 100 oscillates, it will cause the rotation of the element 104 through a quarter revolution. During the idle oscillation of the crank arm 102, the pawl will ride idly over the ratchet wheel and the rotary element 104 will remain stationary in the position into which it has been moved. Thus the oscillation of the arm 100 imparts increments of rotary movement to the element 104 intermittently, with equal periods, between said movements, in which the element 104 is stationary.

The element 104 is provided with a plurality of rows of pockets 109, the rows extending parallel to the axis of rotation of the element 104. The corresponding pockets of the different rows are arranged angularly about the axis of rotation of the element 104, with the corresponding pockets of the different rows in transverse alignment with one another in such angular arrangement about the axis of rotation of the element 104. The corresponding pockets of the different rows diverge from one another in a direction outwardly from adjacent the axis of rotation of the element, and are open at their outer ends. Preferably the pockets of each row are disposed, at their inner or closed ends, against the side wall of the next row of pockets in the direction of rotation of the pockets, this arrangement being clearly shown in Fig. 3.

In each rotation of the element 104 the different rows of pockets 109 will occupy four successive angular positions about their axis of rotation, the four different positions which they occupy during the retraction of the pawl 108 being shown particularly in Figs. 1 and 3. Guard means 110 is disposed beneath the element 104

along the path of travel of the open ends of the pockets, and extends from a position approximately at the level of the axis of rotation of the element at the front side, or the side where the open ends of the pockets are moving downwardly, to a position which is in a level somewhat below the horizontal plane through the axis of rotation of element 104. Thus the guard means 110 along which the open ends of the pockets move while the pockets are in inverted positions, will confine within the pockets any bottles which are placed in the pockets while the pockets are in either of the upper positions, that is, the positions in which the pockets open upwardly. The guard means 110 terminates at the lower edge of the row of pockets which are in inverted position at the rising side, that is, the side adjacent the conveyor, so that bottles contained in the pockets in that position adjacent the conveyor may fall by gravity from the pockets and slide directly into the pockets of the conveyor chain which are in alignment therewith. The shafts 71 and 91, through their connections, operate in synchronized relation to one another so that when the conveyor is stationary, that is, during the time when the feeding pawls 80 are moving backwardly to a new feeding position and the conveyor is stationary, the arm 100 will be moved forwardly to feed the element 104 through one-fourth of a revolution.

Cam 82 is so designed that before the conveyor is fed forwardly by the pawls 80, the arm 100 has moved back into its normal position, ready for a new feeding operation on the element 104, and consequently the pockets 109 are rotated so as to be carried into discharge position in alignment with the pockets of the conveyor only when the conveyor is idle. Since the shaft 91 is operated from the cam 82, the ejectors 94 are fully retracted before the conveyor moves, and the shaft 91 remains stationary until after the conveyor has completed its full increment of movement. The pockets 109 are therefore not moving throughout the entire period while the conveyor is inactive, but only through a portion of the time when this conveyor is inactive. The cam 82 so times the increments of rotation of the element 104, that a row of pockets is not brought into discharge position in alignment with a row of pockets of the conveyor at the loading position, until after the conveyor has completed its full increment of movement and is inactive again.

Where it is desired to use gravity as the major force for ejecting the bottles from the pockets in the rotary element 104, the longitudinal axes of the pockets of the row which is in loading position preferably make an angle of from 20 to 35 degrees to the horizontal. The best angle appears to be approximately 30 degrees, because at that angle of the pockets, the bottles slide freely and promptly from the pockets of the rotary element 104 into the pockets of the conveyor without too great a force which tends to chip or break the bottles as they strike the pockets of the conveyor. It is entirely feasible, however, to have the pockets make a lesser angle to the horizontal, or even be horizontal, when in discharge position but in that case mechanical or additional means must be provided for ejecting the bottles from the pockets of the rotary element 104 and depositing them into the aligned pockets of the conveyor at the loading position.

For this purpose the pockets 109 of each row

are provided with aligned slots 111 which extend from the inner ends of the pockets substantially to the open ends thereof, and rods 112 extend through the pockets of each row and the slots 111 thereof from end to end of the element 104. These rods 112 project slightly from the ends of the element 104, as shown clearly in Fig. 6. Since the slots 111 extend in a direction endwise of the pockets, it will be observed that when the pockets are so positioned that they open upwardly, the rods 112 will descend by gravity to the inner ends of the pockets, where they will be out of the way when bottles are placed in those pockets. When the pockets 109 move downwardly along the guard means 110, however, the rods will tend to fall by gravity and urge the bottles in those pockets downwardly, but the guard means 110 will retain the bottles within the pockets during such movement.

When the pockets 109 reach the loading position, where the guard means 110 no longer is effective to keep the bottles within the downwardly opening pockets, the rods will add their downward urge to that of gravity on the bottles to eject them from the pockets of the rotary element and thus discharge them into the aligned pockets of the conveyor. As the pockets move upwardly, however, from loading position, the rods 112 will move again to the bottoms of the pockets so as to be out of the way when any bottles are placed in the upwardly opening pockets. When the pockets in the horizontal discharge position have an angle of from 25 to 30 degrees, I found that the rods 112 are seldom necessary to insure a discharge of all of the bottles from the pockets 109. This is true even though bottles of different size are used in the pockets of the element 104.

It may in some instances be desirable to guard against any possibility of the bottles sticking in the pockets 109 while in discharge position, and for that purpose I may employ positive means for operating the rods 112 toward the open ends of the pockets 109 while the pockets are in discharge position. The means for accomplishing this positive discharge of bottles will now be described.

An arm 113, Figs. 5 and 6, is fixed on the shaft 91 exteriorly of the housing body at one side thereof. Pivoted to the free end of this arm 113 is a link 114 which extends into the auxiliary housing 106 and terminates in a hook 115 which extends horizontally into a position to engage behind the projecting ends of the rods 112 of those pockets in discharge position. The free end of the link 114 is positioned to ride upon a projecting flange of an angle bar 116 secured to the inner face of the end wall of the housing 106, and inclined downwardly toward the conveyor 11 from adjacent the stub shaft 105. To prevent sidewise displacement of the free end of the hook from the angle strip 116, the latter is provided with a slot 117 which runs for substantially its full length, and a lug 118 depends from the free end of the link 114 and runs freely in the slot 117.

When the shaft 91 moves in a direction to cause a turning movement of the element 104, the hook 115 will ride up the incline provided by the angle strip 116 into a position in which it is between the axis of rotation of the element 104 and the ends of the rods 112 of the pockets 109 that are in discharge or loading position. The rotary increment of movement of the element 104

is completed at the end of the oscillation of the shaft 91 in this one direction, and during such increment of movement a new row of pockets 109 was brought up into the discharge position where it is just uncovered by the guard means 110. At this time the bottles should slide freely by gravity from the pockets in discharge position, aided by the weight of the rod 112 of that row of pockets, but if they do not, as soon as the shaft 91 begins its return movement in the opposite direction back to starting position, the arm 113 will, through the link 114, pull the hook 115 toward the endless conveyor.

Since the rod 112 of that row of pockets in discharge position is then immediately in alignment with the path of movement of the hook 115, the latter will engage the rod 112 and pull it downwardly to the other end of the slots 111 and thus forcibly start or eject all the bottles from that row of pockets 109. The angle of inclination of the bar 116 is of course approximately the same as the angle of inclination of the slots 111 of that row of pockets which is in discharge position adjacent the endless conveyor. The length of the arm 113 is such that for its given arc of oscillation, the hook 115 has the desired rectilinear movement along the angle bar or guide 116.

When the shaft 91 again starts its oscillation in a direction to cause an increment of rotation of the pockets 109 of the rotary loading element 104, the hook 115 will of course move away from the rod 112 of that row of pockets with which it just cooperated to eject the bottles, but since the hook 115 extends sidewise from the link 114, the rotation of the rotary loading element will carry the rod 112 of that row of pockets upwardly in an arcuate path and thus laterally away from the hook 115, so that even if rotation of the pockets 109 should begin before the hook 115 has moved backwardly to any substantial extent, the rod 112 would clear the hook 115 anyway.

The arm 100, at the opposite end of the shaft 91 from arm 113, is forked at its free end, and to the free end of that arm, that is, to one of the forks of the arm 100, one end of a link 119 which corresponds to the link 114 is pivoted. The link 119 at its free end rides upon an angle bar or guide 120 which corresponds to the guide or bar 116 and is provided with a slot 121 which corresponds in function to the slot 117. The free end of the link 119 is provided with a laterally extending hook 122, which corresponds to the hook 115 of the link 114, and this hook 122 engages with the opposite end of the same rod 112 which is engaged by the hook 115. The links 114 and 119 thus operate simultaneously in the same directions and engage both ends of the rod 112 which is associated with that row of pockets 109 which is in discharge position at any time, so as to eject the bottles forcibly from that row of pockets if the bottles do not themselves leave the pockets by gravity.

The cam 81, Fig. 5, on its face toward the housing 10 has an endless cam groove in which runs a suitable cam roller or follower on the arm 123. A link 124 pivoted at one end to arm 123 and a crank arm 125 operate the tilting support 98 for moving the bottle discharged thereon from the endless conveyor 11 into upright position on the conveyor or carrier 99, as usual in machines of this type heretofore.

From the foregoing it will be observed that the bottles disposed in the upwardly opening pockets 109 are moved intermittently, through

increments of a quarter revolution, into the discharge or loading position where the bottles may descend into the aligned pockets of the conveyor 11 in the main housing 10. This makes it possible to load the bottles into both upwardly opening rows of pockets 109 and be certain that the bottles in the pockets when they reach the discharge position will be discharged quickly as a unit into the pockets of the washer conveyor. This is an advantage over the insertion of the bottles into the washer conveyor pockets manually or directly, because the attendant may forget and attempt to insert a bottle into a pocket of the washer conveyor just as the conveyor is starting to move, with the result that the partially inserted bottle may be caught and crushed by its engagement against the housing of the washer.

The attendant will first fill the row of pockets which are about to move along the guard 110, and then proceed to fill the central upstanding row of pockets 109. Thus the attendant will not be as likely to attempt to insert dirty bottles into the pockets as they are about to move along the guard means 110, with resultant decrease of danger of the bottles being caught and crushed, and yet a full charge of bottles will be placed in the washer conveyor at the proper time.

It will be understood that applicant proposes to use safety features to stop the machine in case a bottle is caught while imperfectly inserted into the pockets of the washer conveyor or into the pockets 109, or yielding drives for the washer conveyor 11 or element 104 may be utilized. Such details have been omitted in the present disclosure because they are well known expedients, and in themselves are not a part of the present invention. Their omission from the present disclosure however, is not intended to mean that any of such safety devices cannot be applied to the machine herein disclosed, because such safety devices are incorporated in the machines as actually built and installed.

In many instances it is desirable to subject the dirty bottles to a pre-rinsing operation or to a preliminary cleansing operation before they enter the soaking tank 34. A pre-rinsing or pre-cleansing operation may be incorporated in the loading device, and is a part of this invention. For this purpose the housing 106 extends below the guard means 110, so as to form a drain pan 126, Fig. 3, and a drain pipe 127 leads from this pan to any suitable drain. In the pan 126 and below, but adjacent to, the guard means 110, are a row of spray devices 128 which are arranged to discharge sprays of pre-rinsing or pre-cleansing liquid into the downwardly opening pockets that are temporarily closed by the guard means 110.

The spray devices 128 are so arranged along the path of travel of the open ends of the pockets 109, that when the open ends of the downwardly inclined pockets at the guard means 110 occupy their positions of rest between increments of rotation, as shown in Fig. 3, the spray devices will discharge the rinsing or cleansing liquid upwardly into the interiors as well as against the exteriors of the bottles in those pockets, as clearly illustrated in Fig. 3. Thus the bottles will be subjected to a pre-rinsing or pre-cleansing treatment of substantial duration before they are discharged into the washer conveyor, and any foreign matter in the bottles that can be loosened by this preliminary treatment will drain out into the pan 126 and be carried off, which results in a decrease in the contamination or fouling of the liquid in the soaking tank. This

pre-rinsing liquid may, if desired, be heated to some extent, so as to temper the dirty bottles before they are placed in the washer conveyor and carried into the soaker tank where the soaking liquid may have a relatively high temperature. It will be understood, however, that either hot or cold liquid may be used as the pre-rinsing medium.

Liquid is supplied to the spray devices 128 by a pipe 129, Fig. 1, which passes along a side of the housing 10 to any suitable source of liquid under pressure. In the preferred embodiment, the pipe 129 contains the one of the pair of valves 67 which is furthest from the housing 10, and this valve is operated by the arm 69. The arm 69 has a roller 130 at its free end which is engageable and operable by the periphery of a cam 131 provided on the shaft 71. The cam 131 is so designed that the pre-rinsing or pre-cleansing will take place only during the interval in which the rotary loading element 104 is stationary. The pipe 129 beyond the valve 67 is preferably connected to the pipe 55 which delivers rinsing liquid to the bottles under pressure from the pumps 54, and thus we have a convenient, yet satisfactory source of the rinsing fluid.

In order to provide convenient access to the motor and speed reduction gearing which are placed within the housing 10, the side walls of the housing beneath the pan 57 are provided with openings 132. The top and rear end of the housing may also be provided with a plurality of covers 133 to enable access to be had conveniently to different parts of the interior of the housing 10.

It is believed that the operation of the mechanism will be clear from the foregoing description, but it will be briefly described. With the device assembled as illustrated and above described, the endless conveyor within the housing 10 may be tightened as necessary by first loosening the nuts 26, then turning the nuts 39 to draw the plates 23 outwardly until the conveyor has the desired tautness, after which the nuts 26 are again tightened so as to clamp the adjustable sections 21 of the trackway 18 in the adjusted positions. The positions of the parts shown in the drawings are approximately those occupied at the end of the feeding operation of the endless conveyor, at which time the conveyor feeding pawls 80 are at their forward limit of movement, as shown in Fig. 3. During continued operation of the motor 73, the pawls 80 will be retracted and in retraction will ride idly over the rollers 17 of the conveyor.

The cam 82 will shift the shaft 91 in a direction to carry the arm 100 toward the pre-rinse and loading mechanism, and immediately cause a quarter revolution of the rotary loading element 104. The cam 82 may, if desired, start the rotation of element 104 slightly before the completion of each increment of movement of the washer conveyor, so long as the pockets 109 do not reach discharge position until the washer conveyor has substantially completed its increment of movement. At the same time the links 114 and 119 will ride up the inclined bars or guides 116 and 120 so as to position the hooks 115 and 122 adjacent the axis of rotation of element 104. At the same time, the bottle ejectors 94 will be operated to eject bottles from the pockets of the conveyor aligned therewith, which then fall upon the rest 98. The cam 82 immediately returns the shaft 91 to its former position

shown in the drawings, at which time the bottle ejectors 94 are retracted to normal, inactive positions shown in Fig. 3. At the end of the increment of movement of the loading element 104, the bottles in the row of pockets 109 which have moved into loading position, are discharged into those pockets of the endless conveyor which are then in alignment with those pockets 109 of the loading element.

If the bottles are not so discharged, the hooks 115 and 122 will engage the ends of rod 112 of that row of pockets, and forcibly eject the bottles therefrom as the shaft 91 returns to its normal position. Following the ejection of the bottles from the endless conveyor upon the support 98, the latter is operated to set them upright by cam 81, arm 123, link 124 and crank arm 125. As soon as the rotary loading element 104 has approximately completed each increment of movement, the cam 131, Fig. 1, will depress the arm 69 and open valve 61 to direct the pre-rinsing liquid to the spray devices 128, and the spray so delivered will be directed upwardly into the inverted pockets in alignment therewith and into the interiors of the bottles. Any foreign matter loosened by the pre-rinse liquid will drain out into the pan 126, and be removed in the drain 127.

It will be understood that the guard means 110 may consist of a series of arcuate straps or strips with spaces between them or apertures through which the jets of pre-rinse liquid are delivered into the inverted pockets of the loading element. While the element 104 is inactive, the operator completes the filling of the upright pockets 109, and then continuous operation of the shaft 71 will cause another forward increment of movement of the endless conveyor 11 of the washer. While the endless conveyor 11 is stationary, however, the bottles over pan 63 will be subjected to a chlorine rinse, that is, a rinse with chlorine water, as explained. The screens 47 and 52 are inspected at intervals, after removing the covers 42 of the projecting chambers 39 and 40, and when they become clogged they are removed and cleaned and then replaced by sliding them back into working positions.

It will be observed that with the rotary loading element 104, it is possible to obtain an unusually long period of rest therefor, during which the bottles are subjected to the pre-rinsing liquid.

It will be understood that various changes in the details, which have been herein described and illustrated in order to explain the nature of the invention, may be made by those skilled in the art within the principle and scope of the invention as expressed in the appended claims.

We claim as our invention:

1. In a bottle washing mechanism, bottle conveying means having a plurality of pockets arranged to move in succession through loading position and movable intermittently through increments of movement, a loading element mounted for rotation about an approximately horizontal axis and disposed adjacent said loading position and having a plurality of bottle receiving pockets arranged angularly about the axis of rotation of said element, with the pockets above said axis exposed to receive bottles and opening outwardly and extending outwardly from adjacent the axis of rotation, a guard disposed below said loading element in proximity to the path of travel of the open ends of said loading pockets, so that when said loading element is rotated, any bottles disposed in said

pockets will be retained in the pockets by said guard as the open ends of the pockets move downwardly, the direction of rotation of said loading element being such that the pockets are moving upwardly as they pass said loading position, and said guard terminating approximately at said loading position so that as each pocket moves upwardly past the edge of said guard at said loading position, the open end of that pocket will be uncovered by said guard and any bottle in that pocket may move into a pocket in said conveying means at loading position, means for imparting increments of movement to said conveying means separated by periods of inaction, means synchronized with said movement imparting means for rotating said loading element through a portion of a revolution during each of said periods of inaction and always in said direction and inactive on said loading element while said conveying means is in movement, and spray means disposed adjacent said guard in a position to spray jets of rinsing fluid into the loading pockets through the open ends thereof while said pockets are in inverted position and inactive with their open ends along said guard.

2. In a bottle washing mechanism, the combination of bottle conveying means having a series of conveyor pockets arranged in succession along the same, means for imparting increments of movement to said conveying means intermittently so as to carry the conveyor pockets thereof in succession through a loading position, said pockets having open ends facing outwardly, a rotary loading element mounted for rotation adjacent said loading position and about an approximately horizontal axis, said loading element having a plurality of pockets arranged angularly about said axis of rotation and diverging outwardly with respect to one another from adjacent said axis and with said pockets of said element moving upwardly while passing adjacent said loading position, said pockets of said element being exposed and open at their outer ends whereby they may be loaded with bottles with their open ends outermost when in upper positions and may discharge bottles therefrom when passing said loading position, a guard disposed adjacent the path of travel of said pockets of said element while in inverted positions, means for imparting increments of rotation to said loading element intermittently in synchronized relation to the movements of said conveying means, and spray means disposed along the path of travel of the open ends of said pockets of said element as said pockets travel under said axis with the bottles in inverted positions for spraying inverted bottles in said inverted pockets with a pre-rinse liquid.

3. In a bottle washing mechanism, a pre-rinsing device comprising an element mounted for rotation about an approximately horizontal axis and having a plurality of pockets arranged angularly about said axis of rotation and diverging with respect to one another outwardly from adjacent said axis, the outer ends of said pockets being open for the entry or discharge of bottles, means for rotating said element about said axis by intermittent increments of rotation, but always in the same direction, a guard disposed below said element and extending from a position approximately in the same level as said axis, at the side where the open ends of the pockets are moving downwardly during rotation of said element, beneath said element and partially up the other side of the element, and there ter-

minating, said element in a zone above the level of said axis being exposed for the insertion of bottles into the upwardly opening pockets, said guard being disposed in proximity to the path of travel of the open ends of said pockets so as to confine within said pockets any bottles placed therein while the pockets opened upwardly, throughout movement of said pockets in inverted positions until said pockets reach a selected position in their rising movement determined by the terminus of said guard, whereupon any bottles in the rising pockets may be discharged with the aid of gravity, and spray means located beneath said element for spraying a liquid into the inverted pockets while the pockets are in a position to drain.

4. In a bottle washing mechanism, a pre-rinsing device comprising an element mounted for rotation about an approximately horizontal axis and having a plurality of pockets arranged angularly about said axis of rotation and diverging with respect to one another outwardly from adjacent said axis, the outer ends of said pockets being open for the entry or discharge of bottles, a guard disposed below said element and extending from a position approximately in the same level as said axis, at the side where the open ends of the pockets are moving downwardly during rotation of said element, beneath said element and partially up the other side of the element, and there terminating at a level below said axis of rotation, said guard being disposed in proximity to the path of travel of the open ends of said pockets so as to confine within said pockets any bottles placed therein while the pockets opened upwardly, throughout movement of said pockets in inverted positions until said pockets reach a selected position in their rising movement determined by the terminus of said guard, whereupon any bottles in the rising pockets may be discharged with the aid of gravity, a gravity device associated with each pocket and movable in a direction endwise of the pocket for urging bottles in each inverted pocket downwardly in a discharging direction, and means adjacent said guard for directing a pre-rinse stream of liquid upwardly into each inverted bottle while the bottle is confined in a pocket by said guard.

5. In a bottle washing mechanism, a pre-rinsing device comprising an element mounted for rotation about an approximately horizontal axis and having a plurality of pockets arranged angularly about said axis of rotation and diverging with respect to one another outwardly from adjacent said axis, the outer ends of said pockets being open for the entry or discharge of bottles, a guard disposed below said element and extending from a position approximately in the same level as said axis, at the side where the open ends of the pockets are moving downwardly during rotation of said element, beneath said element and partially up the other side of the element, and there terminating at a level below said axis of rotation, said guard being disposed in proximity to the path of travel of the open ends of said pockets so as to confine within said pockets any bottles placed therein while the pockets opened upwardly, throughout movement of said pockets in inverted positions until said pockets reach a selected position in their rising movement determined by the terminus of said guard, whereupon any bottles in the rising pockets may be discharged with the aid of gravity, 75

spray means located beneath said element for spraying a liquid into the inverted pockets while the pockets are in a position to drain, and a gravity device associated with each pocket and movable in a direction endwise of the pocket for urging bottles in each inverted pocket downwardly in a discharging direction.

6. In a bottle washing mechanism or the like, an element mounted for rotation about an approximately horizontal axis and having a plurality of bottle receiving pockets arranged angularly about said axis of rotation of said element, and diverging from one another outwardly from adjacent said axis, the outer ends of said pockets being open, a guard beneath said element and extending along the path of travel of the open ends of said pockets from a position beginning at one side of the element where the pockets are descending, to the opposite side where the pockets are rising and there terminating, whereby bottles loaded in any of said pockets while those pockets are upright will be confined by said guard in said pockets while travelling along said guard, and then released at the rising side, and means for imparting increments of rotary movement to said element, always in the same direction, and spray means disposed to discharge a liquid into the downwardly opening pockets against bottles confined therein by said guard.

7. In a bottle washing mechanism or the like, an element mounted for rotation about an approximately horizontal axis and having a plurality of bottle receiving pockets arranged angularly about said axis of rotation of said element, and diverging from one another outwardly from adjacent said axis, the outer ends of said pockets being open, a guard beneath said element and extending along the path of travel of the open ends of said pockets from a position at approximately the midheight point of said element at one side of the element where the pockets are descending, past the lowest point of said element to the opposite side where the pockets are rising and there terminating at an intermediate point on the rising side of said element, whereby bottles loaded in any of said pockets while upright will be confined by said guard in said pockets while travelling along said guard, and then released at an intermediate point on the rising side to be discharged, bottle conveying means having a series of conveyor pockets arranged in succession along the same, means for imparting increments of movement to said conveying means intermittently, so as to carry the conveyor pockets in succession into approximate alignment with the pockets of said element as the latter are rising and clear said guard, so that bottles discharged from the rising pockets of said rotary element may move into pockets of said conveyor, means for moving said rotary element in the same direction through increments of rotation intermittently but in synchronized relation to the movement of said conveyor means, with said conveyor means inactive while said rotary element is in motion and vice versa, and a spray device associated with said guard for spraying a liquid into the pockets while inverted and adjacent said guard.

8. In a bottle washing mechanism or the like, an element mounted for rotation about an approximately horizontal axis and having a plurality of bottle receiving pockets arranged angularly about said axis of rotation of said ele-

ment, and diverging from one another outwardly from adjacent said axis, the outer ends of said pockets being open, a guard beneath said element and extending along the path of travel of the open ends of said pockets from a position at approximately the midheight point of said element at one side of the element where the pockets are descending, past the lowest point of said element to the opposite side where the pockets are rising, and there terminating in an intermediate point on the rising side, whereby bottles loaded in any of said pockets while the pockets are opening upwardly, and with the open ends of the bottles outermost, will be confined by said guard in said pockets while travelling along said guard, and then released at the rising side to be discharged, bottle conveying means having a series of conveyor pockets arranged in succession along the same, means for imparting increments of movement to said conveying means intermittently, so as to carry the conveyor pockets in succession into approximate alignment with the pockets of said element as the latter are rising and have cleared said guard, so that bottles released from the rising pockets of said rotary element may enter into pockets of said conveyor, means for moving said rotary element always in the same direction through increments of rotation intermittently but in synchronized relation to the movement of said conveyor means, means operable while pockets of said conveyor means and element are aligned as the rising pockets of said element clear said guard, for urging bottles released by said guard into the aligned pockets of said conveyor means, and a spray device associated with said guard for spraying a liquid into the pockets while inverted and adjacent said guard.

9. In a bottle washing mechanism, a loading element mounted for rotation in one direction about an approximately horizontal axis, and having a plurality of bottle receiving pockets arranged angularly about said axis, in approximate transverse alignment with one another, diverging from one another outwardly from said axis, and open at their outer ends, means for rotating said element in one direction by intermittent increments of movement, guard means extending beneath said element from close proximity to a horizontal plane through said axis and close to the downwardly opening ends of said pockets to a point well up on the rising side of said element for confining bottles in said pockets while said pockets pass beneath said axis of said element to a desired discharge position at the side where the pockets rise, and spray means for directing a spray of liquid into each of said pockets while in one inverted position along said guard means.

10. In a bottle washing mechanism, a loading element mounted for rotation in one direction about an approximately horizontal axis, and having a plurality of bottle receiving pockets arranged angularly about said axis, in approximate transverse alignment with one another, diverging from one another outwardly from said axis, and open at their outer ends, the base of each pocket abutting against the side of the next adjacent pocket in the direction of rotation, guard means extending beneath said element and close to the downwardly opening ends of said pockets for confining bottles in said pockets while said pockets pass below the axis of said element to a desired discharge position at the side where

5 the pockets rise, means for imparting rotary increments of movement to said element intermittently, individual gravity actuated means associated with each pocket for engaging and urging outwardly any bottles in that pocket while said pocket is in said discharge position, and means for positively actuating said gravity actuating means of the pocket in unloading position if it fails to operate by gravity.

10 11. In a bottle washing mechanism or the like, a loading element mounted for rotation about an approximately horizontal axis and having a plurality of rows of bottle receiving pockets with the rows running approximately parallel to said axis and the different rows arranged angularly about said axis, said pockets of the different rows diverging from one another outwardly from adjacent said axis, the outer ends of said pockets being open, a guard beneath said element and extending along the path of travel of the open ends of said pockets to confine bottles therein from a position at one side of the element where the pockets are descending to the opposite side where the pockets are rising, a washer having a conveyor with rows of pockets therein movable past one side of said element in proximity to the open ends of the pockets thereof and beyond the end of said guard at the rising side thereof, means for imparting increments of movement to said conveyor to bring successive rows of pockets thereof into aligned positions with pockets of said element at the rising side thereof, a member extending along each row of pockets and shiftable in a direction lengthwise of the pockets of that row to eject bottles from that row, means operable in synchronized relation to the active and inactive periods of movement of said conveyor for imparting increments of rotation to said element in a manner to cause the pockets to rise at the side adjacent said conveyor, and means also operable by said rotating means between the increments of rotation of said element for engaging the member of the row of pockets at the side nearest the conveyor and pulling that member in a direction outwardly of the pockets to discharge bottles therefrom and into the pockets of said conveyor.

15 12. In a bottle washing mechanism or the like, a loading element mounted for rotation about an approximately horizontal axis and having a plurality of rows of bottle receiving pockets with the rows running approximately parallel to said axis and the different rows arranged angularly about said axis, said pockets of the different rows diverging from one another outwardly from adjacent said axis, the outer ends of said pockets being open, a guard beneath said element and extending along the path of travel of the open ends of said pockets to confine bottles therein from a position at one side of the element where the pockets are descending to the opposite side where the pockets are rising, a washer having a conveyor with rows of pockets therein movable past one side of said element in proximity to the open ends of the pockets thereof and beyond the end of said guard at the rising side thereof, means for imparting increments of movement to said conveyor to bring successive rows of pockets thereof into aligned positions with pockets of said element at the rising side thereof, a member extending along each row of pockets and shiftable in a direction lengthwise of the pockets of that row to eject bottles from that row, means operable in synchronized relation to the active and inactive periods of movement of said con-

veyor for imparting increments of rotation to said element in a manner to cause the pockets to rise at the side adjacent said conveyor, and means also operable by said rotating means between the increments of rotation of said element for engaging the member of the row of pockets at the side nearest the conveyor and pulling that member in a direction outwardly of the pockets to discharge bottles therefrom and into the pockets of said conveyor, said last named means including a hooked member which allows advance of the pocket member in a direction outwardly of the pockets separately from said hooked member, whereby said pocket member is free to move by gravity, but if not moved by gravity will be positively moved by said hooked member.

13. In a bottle washing mechanism or the like, a loading element mounted for rotation about an approximately horizontal axis and having a plurality of rows of bottle receiving pockets with the rows running approximately parallel to said axis and the different rows arranged angularly about said axis, said pockets of the different rows diverging from one another outwardly from adjacent said axis, the outer ends of said pockets being open, a guard beneath said element and extending along the path of travel of the open ends of said pockets to confine bottles therein from a position at one side of the element where the pockets are descending to the opposite side where the pockets are rising, a washer having a conveyor with rows of pockets therein movable past one side of said element in proximity to the open ends of the pockets thereof and beyond the end of said guard at the rising side thereof, means for imparting increments of movement to said conveyor to bring successive rows of pockets thereof into aligned positions with pockets of said element at the rising side thereof, a member extending along each row of pockets and shiftable in a direction lengthwise of the pockets of that row to eject bottles from that row, a ratchet wheel connected to said element, a pawl device operating on said ratchet wheel, a link connected to said conveyor moving means for movement generally endwise thereby, said pawl device being active on said ratchet wheel to move it when said conveyor is idle, a hooked member also connected to said moving means for operation with said link and free to swing vertically and be hooked to the member of the row of pockets at the side adjacent the conveyor as such pockets move successively into those positions, and means for guiding said hooked member into hooked engagement with the member of the row of pockets at the side adjacent said conveyor during the propelling action of said pawl device on said ratchet wheel and operable on the pocket member with which it is hooked in a direction outwardly of the pockets during the movement of said link while said pawl device is inactive on said ratchet wheel.

14. In a bottle washing mechanism or the like, a loading element mounted for rotation about an approximately horizontal axis and having a plurality of rows of bottle receiving pockets with the rows running approximately parallel to said axis and the different rows arranged angularly about said axis, said pockets of the different rows diverging from one another outwardly from adjacent said axis, the outer ends of said pock-

ets being open, a guard beneath said element and extending along the path of travel of the open ends of said pockets to confine bottles therein from a position at one side of the element where the pockets are descending to the opposite side where the pockets are rising, a washer having a conveyor with rows of pockets therein movable past one side of said element in proximity to the open ends of the pockets thereof and beyond the end of said guard at the rising side thereof, means for imparting increments of movement to said conveyor to bring successive rows of pockets thereof into aligned positions with pockets of said element at the rising side thereof, a member extending along each row of pockets and shiftable in a direction lengthwise of the pockets of that row to eject bottles from that row, a ratchet wheel connected to said element, a pawl device operating on said ratchet wheel, a link connected to said conveyor moving means for movement generally endwise thereby, said pawl device being active on said ratchet wheel to move it when said conveyor is idle, a hooked member also connected to said moving means for operation with said link and free to swing vertically and be hooked to the member of the row of pockets at the side adjacent the conveyor as such pockets move successively into those positions, and means for guiding said hooked member into hooked engagement with the member of the row of pockets at the side adjacent said conveyor during the propelling action of said pawl device on said ratchet wheel and operable on the pocket member with which it is hooked in a direction outwardly of the pockets during the movement of said link while said pawl device is inactive on said ratchet wheel.

15. In a bottle washing mechanism or the like, a loading element mounted for rotation about an approximately horizontal axis and having a plurality of rows of bottle receiving pockets with the rows running approximately parallel to said axis and the different rows arranged angularly about said axis, said pockets of the different rows diverging from one another outwardly from adjacent said axis, the outer ends of said pockets being open, a guard beneath said element and extending along the path of travel of the open ends of said pockets to confine bottles therein from a position at one side of the element where the pockets are descending to the opposite side where the pockets are rising, a washer having a conveyor with rows of pockets therein movable past one side of said element in proximity to the open ends of the pockets thereof and beyond the end of said guard at the rising side thereof, means for imparting increments of movement to said conveyor to bring successive rows of pockets thereof into aligned positions with pockets of said element at the rising side thereof, a member extending along each row of pockets and shiftable in a direction lengthwise of the pockets of that row to eject bottles from that row, and operable to cause simultaneous ejection of all bottles from the pockets of that row, and means for directing streams of liquid into the bottles held in inverted positions in said pockets by said guard.

16. A pre-rinse device for bottle washing machines, and the like, which comprises pocket means for receiving bottles in generally upright positions, moving them in a desired path through inverted positions always in the same direction to discharge positions, and there releasing them, and means disposed beneath said path of travel

of said pocket means and operable to direct a pre-rinse stream of liquid into the inverted bottles at a selected point in said path.

17. In the method of pre-rinsing bottles and loading them into pockets of a conveyor of a washing machine, that improvement which comprises moving bottles from generally upright positions in the same direction in a desired path

through inverted positions and towards upright positions to a desired discharge point, and directing a pre-rinse stream of liquid into the bottles while in inverted positions at an intermediate point in said path.
